A. PERRI.
SHOE HEELING METHOD AND PRODUCT THEREOF.
APPLICATION FILED MAY 6, 1918.

Patented Dec. 24, 1918.

UNITED STATES PATENT OFFICE.

ANGELO PERRI, OF GROVELAND, MASSACHUSETTS, ASSIGNEE TO BEECH SHOE MANUFACTURING COMPANY, OF EGSTON, MASSACHUSETTS, A CORPORATION OF MAINE.

SHOE-HEELING METHOD AND PRODUCT THEREOF.

1,239,054.

Specification of Letters Patent. Patented Dec. 24, 1918.

Application filed May 8, 1918. Serial No. 222,728.

To all whom it may concern:

Be it known that I, ANGELO PERRI, a citizen of the United States, residing at Groveland, in the county of Essex and State of Massachusetts, have invented certain new and useful Improvements in Shoe-Heeling Methods and Products Thereof, of which the following is a specification, reference being had thereto to the accompanying drawing.

This invention relates to a novel shoe heel method and product thereof. The more complete objects are to improve the method of preparing and attaching the heel to the shoe, and the novel article or product which permits the practice of such method. The more detailed objects and advantages of the present improvement will be made clear in the hereinafter following description of one illustrative embodiment thereof, or will be apparent to those skilled in the art.

To the attainment of such objects and advantages the present invention consists in the novel features of method, steps, manipulations, arrangements and resulting product or article, as hereinafter explained, described, illustrated or claimed.

In the accompanying drawings showing one embodiment of the improvement, Figure 1 is a side elevation of a built-up heel in the rough. Fig. 2 is a similar view, partly broken away, of the same heel after vertical compression of the heel and the concave shaping of the lower surface thereof. Fig. 3 is a similar view of the same heel, partly broken away, showing the piercing of a series of short-depth nail holes in a particular manner, that is, divergingly, by a gang of divergingly actuated awls. Fig. 4 is a top plan view of the heel at the stage of the process shown in Fig. 3, but with the awls extracted. Fig. 5 is a view similar to Fig. 3, but showing a series of nails inserted loosely in the short-depth diverging nail holes, and, diagrammatically, a driver about to act upon the nails. Fig. 6 is a similar view shows the subsequent stage in the preparation of the heel when the nails have been driven almost, but not quite, through the depth of the heel. Fig. 7 in a similar view shows the later stage in which the heel has been applied to the inverted shoe and the nails driven sufficiently farther to pass through the sole and clench within. Fig. 8

in a partial, similar view shows the next stage, in which the protruding nail ends at the top are deflected or bent into parallelism or at right angles to the heel top. Fig. 9 in similar view shows the heel top lift 60 driven into place upon the protruding nail tops. Fig. 10 is a top view showing the same stage as in Fig. 9. These two figures show the shoe completed, except for the heel trimming, which, however, is indicated in dotted lines in Fig. 9.

As will be observed from the drawings, the invention will be shown as applied in the manufacture of high-heeled ladies' shoes, and that is the more particular application of the improvement, although some of its features might be otherwise employed. Heretofore in the manufacture of such shoes a series of nails has been driven through the heel from the top or small end in vertical parallel directions, with the result that the actual attachment of the heel to the shoe at the bottom or large end of the heel is through a series or circle of attachment points so close together and so far from the periphery of the heel at this point as to give a very unstable and insecure fastening.

It has also been proposed to drive nails divergingly through certain forms of heel into the shoe, for example, as in expired Raymond Patent 355,027, of December 28, 1886, but as practised the projecting nail tops stand convergingly and are unadapted to properly engage with and securely hold the heel toplift. An object of the present invention is to overcome the defects in prior methods and products.

Both the method and product will be best understood by reference to the illustration in the drawings, by the aid of which I will now describe in detail the present invention.

Fig. 1 shows the rough heel, composed of the usual series of lifts, 11 to 20, inclusive. The exact structure of this forms no part of the present invention and need not be described in detail. As is usual, the top lift 21 is not applied originally, but is shown in Figs. 9 and 10 as applied finally after the attachment of the heel to the shoe.

The first step in preparing the heel for attachment is the compressing step, which is indicated in Fig. 2, first by the fact that the heel in that figure is of shorter vertical dimension than in Fig. 1, and second by the

concave underside, which is shaped in a well-known manner to fit the convexly curved exterior of the shoe, to which the heel is to be attached. This concaving process results in a recess 22.

The next step according to this invention is preferably to pierce a series of diverging nail holes 23, as shown in Figs. 3 and 4, although in some cases the preliminary 10 piercing of the nail holes might be omitted, and the nails driven directly in diverging directions. As shown in Fig. 3, the pierced holes may be formed by a gang of awls 24, working simultaneously in a manner devised 15 by me; although the holes might be pierced one at a time by the same or different awls. It is not necessary to pierce the nail holes to the full depth of the heel, but only to a short depth, as indicated, the nails being 20 able to force their own way accurately through the remainder of the thickness of the heel. The pierced short-depth holes take the nails and serve as effective guides to insure that the nails will continue to 25 travel in a predetermined diverging manner, as they are driven.

The next step is to remove the awls 24 and insert in the nail holes 23 a series of nails 25, which may be square-shanked nails without 30 heads, tapering slightly from the top to the bottom, and of sufficient length for attaching purposes. The several nails may vary in length, according to the varying distances they have to be driven. Thus, there may be, 35 for example, seven nails altogether, the three rearmost of a longer length, and the other four of a shorter length.

The next step is the driving of the nails substantially through the heel, but preferably 40 not emerging, as it is desirable to assemble the heel and shoe after this stage in the process, and complete the driving and attachment as a separate operation. Fig. 6 shows the nails 25 as driven downwardly 45 substantially to the emerging point, and conventionally I have illustrated a driver 26 in Fig. 5 capable of this step, or a plurality of drivers 27, 28, in Fig. 6. They may operate by a series of blows directed toward 50 the nail tops, or a single forcible blow or thrust.

The next step is to assemble the prepared heel with the shoe in the manner indicated in Fig. 7. The shoe is shown as comprising 55 a convexly curved outsole 29, insole 30, and upper 31. The shoe at this stage preferably contains a wooden last with metallic bottoms to serve as an anvil to turn and clenche the 60 nails, although other forms of anvil or clenching means may be employed.

When the heel and shoe have been assembled, as described, the driving of the nails 25 is completed in the manner indicated in Fig. 7, the nails being thrust downwardly 65 until their lower ends are clenched within

the shoe sole. Preferably this is so done as to leave all of the nails protruding upwardly at 32 beyond the top of the heel for a slight distance, as indicated in Fig. 7, although these protruding ends might in some cases be omitted or removed where the top lift is omitted or is otherwise attached.

The protruding nail tops 32 in Fig. 7 now stand convergingly, and the next step in my method is to bend or deflect each of these so 75 that they stand parallel to each other, and preferably at right angles to the top surface of the heel, as shown at 33 in Fig. 8, which illustrates this stage in the method.

Sometimes I prefer to complete the driving action to the point indicated in Fig. 7 and perform the bending action, as indicated in Fig. 8, in substantially a single operation, by means of suitable drivers, benders or dies, the bending being performed toward the completion of the driving and as a continuation of the action thereof; and it will be understood that during the driving of the nails at all stages and until the Fig. 8 stage has been arrived at, 90 the several nails may be laterally supported or braced or guided against undue strain, breakage or undesirable bending. The preferred means that I have devised for this purpose is not herein shown.

With the protruding nail ends 33 standing thus parallel to each other and having no heads, the subsequent step of driving the top lift 21 to engage the protruding ends on top of the heel is easily performed by a simple striking or pressing action; it being understood that glue has been previously applied between the heel top and the top lift before the latter is pressed into place.

The shoe is now completed, with the exception of the usual heel trimming operations, indicated by the dotted line 34 in Fig. 9, which operations, however, constitute no part of the present invention. The shoe or product, whose manufacture has thus been 105 described, comprises a heel substantially smaller at the top than at the base, and secured to the shoe by a series of attaching nails having a diverging arrangement, so that the attachment points are spaced or arranged over a much larger circumference or area than the points at which the nails are driven through the small or top end of the heel.

I have herein used relative terms, upward, 120 downward, top, bottom, base, on the assumption that the shoe is inverted as shown, so that the part of the heel usually known as the tread is considered as the top, and the seat of the heel as the bottom or base.

I prefer to carry out the described principles of this invention by a machine of a type in which the heels are successively inserted by hand or fed in automatically, and which machine thereupon shifts each heel 125 130

to a new location where the described compressing action takes place, and then again shifts the heel to a new location where a suitable piercing means operates upon it, followed by another shift, and thereafter the insertion and the partial driving of the nails. I prefer at this point to have the heels discharged or removed from the machine and assembled elsewhere in a second machine with the shoe, where the final driving and attaching operations are performed, the bending of the protruding nail tops, the application of the top lift, and finally the trimming of the heel.

15 A machine suitable for carrying out certain embodiments of the present invention is fully shown and claimed in my copending application Serial No. 262,104, filed November 11, 1918.

20 It will thus be seen that I have described a shoe heelng method and the product thereof embodying the principles of the present invention and attaining the objects and advantages before described. Since many matters of arrangement, combination, order or 25 number of steps of procedure and details may be modified without departing from the underlying principles, I do not desire to restrict the invention to such features except 30 in so far as specified in the appended claims.

What is claimed is:

1. A shoe heelng method comprising driving a series of nails divergently into the heel top so as to give a line of attachment 35 to the sole proximate to the heel periphery, leaving the converging nail tops outstanding slightly and bending them into substantial parallelism, and forcing a top lift into place upon said nail tops.

2. A shoe heelng method comprising 40 piercing diverging holes into the heel top, inserting nails therein, and driving the nails divergently into the sole, leaving the converging nail tops outstanding slightly and bending them into substantial parallelism, 45 and forcing a top lift into place upon said nail tops.

3. A shoe heelng method comprising 50 piercing diverging short-depth holes in a series around the heel top, inserting nails 55 therein, driving the nails nearly to emerge, applying the heel to the shoe, and completing the driving and clenching of the nails, leaving the converging nail tops outstanding slightly and bending them into substantial 55 parallelism, and forcing a top lift into place upon said nail tops.

4. A shoe comprising sole and heel, said heel consisting of body portion and top lift and attaching nails passing completely 60 through the heel body portion into the sole at different angles, the top ends of the nails being bent relatively to their main portions into parallel relation, and there engaging in 65 the heel top lift.

5. A shoe comprising sole and heel, said heel consisting of body portion and top lift and attaching nails extending from a series of points at the top of the body portion divergently to a series of further spaced points 70 where they pass from the heel base into the sole, the top ends of the nails being bent relatively to their main portions into parallel 75 relation, and there engaging in the heel top lift.

In testimony whereof, I have affixed my signature hereto.

ANGELO PERRI.
